AUTOMATIC RECORD CHANGER FOR
PHONOGRAHS

Harald Valdemar Alexandersson, Lidingo, Sweden, assignor to Svenska Aktiebolaget Gasacumulator, Lidingo, near Stockholm, Sweden, a corporation of the Kingdom of Sweden

Application February 29, 1944, Serial No. 524,354
In Sweden February 20, 1943

Section 1, Public Law 690, August 8, 1946
Patent expires February 20, 1963

3 Claims. (CL. 274—10)

1

My invention relates to an arrangement for feeding records in automatic record changers for phonographs.

For feeding records in automatic record changers for phonographs it has been proposed to use a substantially vertical centre pin, which has, however, been given such a form, that the part of the centre pin below the point of support for the stacked records, and the part above said point were not coaxial. In this way the upper end of the lower part, and the lower end of the upper part, form two horizontal surfaces, the distance between the surfaces being only a little greater than the thickest record which the device is adapted to handle.

In a known construction of the above mentioned kind the means for feeding the record from lay up position into feed down position comprises a shaft, turnable within or without the lower part of the centre pin, said shaft being connected with a member arranged between the surfaces of such a form that the movement of the turnable shaft causes, by co-operation between the member and the centre perforation of the record, the record to be brought from lay-up position into feed down position.

This construction, however, is not satisfactory due to the fact that the above mentioned member cannot be given a fully circular or in other respects well rounded form for the reason that the upper part of the centre pin is carried by the lower part, and the connection part between the upper and the lower part of the centre pin therefore occupies a part of the place necessary for phonographs a fully circularly round member in the above mentioned construction. Because the member hence cannot be made round, it is apt to wear the edge of the centre perforation of the record, so that the record will not remain in the position carried by the centre pin but, due to its enlarged centre perforation, will be fed down by itself or by slight vibration or shaking at a time when no feeding down is intended. The record then may fall down upon the pick-up arm during the playing, with the result that not only the record itself may be destroyed but also the record being played and in some cases also the pick-up arm may be damaged.

In order to overcome these disadvantages, it has been suggested to make the member circular, and to do without the fixed connection between the upper and the lower parts of the centre pin, the upper part therefor being carried by other means than the lower part. Such means, however, in order not to interfere with placing the

2

records in lay-up position, has been made as a bridge, which may be swung in vertical direction about a shaft outside the periphery of the turntable. This construction also has not been successful, as it has not given the required stability, and as a consequence thereof undesirable displacements have easily taken place between the upper and lower parts of the centre pin or post member, the proper functioning of the arrangement thereby being made impossible. The arrangement moreover is rather large, heavy, technically complicated and expensive to manufacture.

The present invention refers to an arrangement 15 for feeding down records in automatic record changers, provided with a substantially vertical centre pin in which the above disadvantages are not present. In the arrangement according to the invention the lower and the upper parts of 20 the centre pin are directly rigidly connected to each other. The lower part, however, carries a turnable, preferably concentrically arranged shaft, which may either be arranged within or outside the fixed lower part of the centre pin. 25 The turnable shaft, however, is not rigidly connected with the member which causes the feeding down of the record, but the member and the shaft are separated from each other but coupled together by means of a motion transferring coupling. In this manner it is made possible to have the member and the turnable shaft turn about 30 different centres, which makes it possible to make the member as a circular or otherwise suitably rounded disc, adapted to the form of the centre 35 perforation of the record, as will be evident from the following. As a coupling between the turnable shaft and the disc there is provided a slot, arranged in one of said parts, co-operating with a pin, arranged on the other part.

40 The invention is further described below in connection with the annexed drawing, in which Fig. 1 shows an arrangement according to the invention, partly in section, and Fig. 2 shows the central part of the said arrangement in an enlarged scale.

In the drawing 10 indicates the upper part of 45 the centre pin or post member, which is provided with the horizontal surface 12, facing downwardly. The lower part consists of a fixed core 16 and a hollow shaft 17 turnable about the core and has an upper horizontal surface 11. Thus the pin comprises a vertical member having laterally offset upper and lower parts. Three records 13, 14 and 15 are shown in stacked or 50 lay-up position.

Between the lower and the upper part of the centre pin that is, in the space between the surfaces 11 and 12, there is arranged a disc 25. This is provided with an eccentric perforation 30, through which extends a pin 26, the disc 25 thus being rotatable eccentrically about the pin 26. The pin 26 rigidly connects the fixed core 16 of the lower part of the centre pin with the upper part 10 of the centre pin. The pin 26 may be integral with the core 16 and may be driven into a hole in the upper part 10, as is shown in Fig. 2. The disc 25 is provided with a groove 27, for instance diametrically arranged, into which extends a projection 28 from the turntable hollow shaft 17.

The operation of the above described apparatus is as follows. The disc 25 is received within the centre perforation of the lowest record 13. When the hollow shaft 17 is turned, the projection 28 cooperating with the groove 27 causes rotation of the eccentrically mounted disc 25, whereby it is turned to the position in which it axially coincides with the lower part 16, 17 of the centre pin. During this movement it brings the record 13 with it, so that this record is laterally displaced to bring its centre perforation in alignment with the lower part of the centre pin 16, 17. The record 13 therefore falls down on to the turntable. The disc 25 by further turning of the hollow shaft 17 is brought again into the position shown in the drawing, and the next record 14 will fall down to the place, which in the drawing is shown as occupied by the record 13. Thereafter the operation may be repeated.

While I have shown and described one more or less specific embodiment of my invention, it is to be understood that this has been done for purposes of illustration only, and that the scope of my invention is not to be limited thereby, but is to be determined from the appended claims.

What is claimed:

1. Feeding down mechanism for an automatic record changer, comprising a substantially vertical post member having laterally offset upper and lower parts, the adjacent ends of said parts having substantially horizontal surfaces spaced apart a distance greater than the thickness of one record and less than the thickness of two records, said lower part comprising a rotatable hollow shaft and a core within a said hollow shaft, a pin located eccentrically with respect to said core and rigidly connecting said core with said upper part, a circular disc eccentrically and rotatably mounted on said pin in the space between said surfaces, the thickness of said disc being not greater than that of one record, and eccentric coupling means for transmitting rotation from said hollow shaft to said disc.

2. Feeding down mechanism for an automatic record changer, comprising a substantially vertical post member having laterally offset upper and lower parts, the adjacent ends of said parts having substantially horizontal surfaces spaced apart a distance greater than the thickness of one record and less than the thickness of two records, said lower part comprising a rotatable hollow shaft and a core within a said hollow shaft, a pin located eccentrically with respect to said core and rigidly connecting said core with said upper part, a circular disc eccentrically and rotatably mounted on said pin in the space between said surfaces, the thickness of said disc being not greater than that of one record, and eccentric coupling means comprising a slot formed in said disc and a projection on said hollow shaft for transmitting rotation from the hollow shaft to the disc.
3. Feeding down mechanism for an automatic record changer, comprising a substantially vertical post member having laterally offset upper and lower parts, the adjacent ends of said parts having substantially horizontal surfaces spaced apart a distance greater than the thickness of one record and less than the thickness of two records, said lower part comprising a rotatable hollow shaft and a core within a said hollow shaft, a pin located eccentrically with respect to said core and rigidly connecting said core with said upper part, a circular disc eccentrically and rotatably mounted on said pin in the space between said surfaces, the thickness of said disc being not greater than that of one record, the lower surface of said disc being formed with a diametrically extending groove, and a projection eccentrically located at the upper end of said hollow shaft and engaging said groove.

Certificate of Correction

June 6, 1950

Patent No. 2,510,455

HARALD VALDEMAR ALEXANDERSSON

It is hereby certified that error appears in the printed specification of the above numbered patent requiring correction as follows:

Column 4, line 58, list of references cited, under "Foreign Patents" for the patent number "590,941" read 520,941;

and that the said Letters Patent should be read as corrected above, so that the same may conform to the record of the case in the Patent Office.

Signed and sealed this 24th day of October, A. D. 1950.
